UNITED STATES PATENT OFFICE.

ALBERT J. SWEET, OF WASECA, MINNESOTA.

DOOR HOLDER.

Application filed June 1, 1925. Serial No. 38,919.

This invention relates to a door holder and particularly a device applicable to such a door as a garage door for holding the same in open position.

5 It is an object of this invention to provide a simple and efficient door holding means comprising few parts and one which is very easily operated.

10 It is more specifically an object of this invention to provide a door holding device comprising a rod carried on the exterior of and spaced from the door having a downwardly extending recess formed therein and a rod pivoted at one end to the wall of a 15 building and having an eyelet at its other end slidable on said first mentioned rod and adapted to drop into said recess.

These and other objects and advantages of the invention will be fully set forth in 20 the following description made in connection with the accompanying drawing, in which like reference characters refer to the same parts throughout the different views, and in which

25 Fig. 1 is a perspective view showing a door having the invention applied thereto, said door being in open position;

Fig. 2 is a view in front elevation showing a portion of a pair of doors in closed 30 position with the invention applied thereto; and

Fig. 3 is a horizontal section taken on the line 2—2 of Fig. 2.

Referring to the drawings, the wall of 35 a building is indicated as 4 having a door jamb 5 to which is hinged, in the usual manner, a door 6, said door and jamb 5 having secured thereto the hinges 7. The door 6 is shown as one of a pair of double 40 doors, the other oppositely swinging door being partly shown as 8. Doors 6 and 8 are adapted to be connected when closed by a suitable lock or latch 9.

In accordance with the present invention, 45 the doors 6 and 8 have secured thereto a rod 10. This rod is shown as having an intermediate portion spaced from the surface of door 6, the ends of said rod being offset or bent substantially at right angles and 50 having flattened portions 10^a apertured to receive fastening screws or bolts by which said rod is attached to the door. Rod 10 thus extends across or transversely of the door substantially horizontal and said rod 55 is formed adjacent the end toward the free edge of the door, with a downwardly ex-

tending recess 10^b. While this recess may be variously formed, in the embodiment of the invention illustrated, it is shown as formed by bending rod 10 downwardly into 60 a U-shaped formation. Co-operating with rod 10 is another member or rod 11 having one end pivotally connected to a fixed member 12 spaced from the hinged edge of the door. While the rod 11 may be variously 65 attached, in the embodiment of the invention illustrated it is shown as having an eyelet 11^a at its end passing through an eyelet at the outer end of the member 12, which outer member may be secured to the wall 70 75 4. The other end of rod 11 has an eyelet 11^b formed thereon, the plane of which is disposed at an angle to rod 11, the same being shown as disposed at an angle of approximately 45 degrees. The eyelet 11^b embraces the rod 10 and is slidable on the intermediate portion thereof, which is spaced from the door 6.

When the door 6 is closed, the eyelet 11^b, as shown in Fig. 2, will be adjacent the end of rod 10, which is nearest the hinged side of the door. The door can be locked or fastened in closed position as usual. When the door is open and swings on its hinges, eyelet 11^b merely slides on rod 10, rod 11 swinging about its end disconnected from member 12. When the eyelet 11^b reaches the recess 10^b, it drops therein and when in this position, the rod 11 holds the door in fixed position. The eyelet 11^b is securely held 90 between the parallel sides of recess 10^b and said recess will be of such dimension that the eyelet will fit snugly therein. All motion of the door is thus prevented, when the eyelet is in the recess. When it is desired 95 to close the door, the rod 11 is merely lifted to remove eyelet 11^b from recess 10^b and said eyelet then slides upon rod 10 until the door is in its closed position. The inclined position of eyelet 11^b relative to rod 11 permits the same to readily be lifted from the recess. 100

From the above description, it is seen that applicant has provided a very simple and efficient door holding means and one that 105 operates easily and automatically to hold the door in open position. The parts of the device are very few and are easily and inexpensively made from standard rod material and the parts are easily and quickly installed. The device is very durable and requires no attention for maintenance. The 110

same has been actually demonstrated in actual practice and has been found to be very successful and efficient.

It will, of course, be understood that various changes may be made in the form, details, arrangement and proportions of the parts without departing from the scope of applicant's invention, which, generally stated, consists of the novel parts and combinations of parts disclosed and defined in the appended claims.

What is claimed is:—

1. A door holder comprising a round rod formed to be attached to the door at its ends and spaced from the door at the portion between said ends, said rod adjacent one end of said portion being bent downwardly into U-shape to form a recess, another rod pivoted to a stationary member adjacent and beyond the hinged side of said door and hav-

ing an eyelet at its other end disposed at an angle thereto, said eyelet embracing said first mentioned rod and slidable thereon and adapted to drop into said recess to hold the door in open position.

2. A door holder comprising a rod secured to a door at its ends and having an intermediate portion spaced from said door and extending horizontally transversely thereof and parallel thereto and formed with a downwardly extending recess therein adjacent one end of said portion, and a rod pivotally connected at one side of said door and having an eyelet at its other end slidable on said first mentioned rod and adapted to drop into said recess and hold said door in open position.

In testimony whereof I affix my signature.

ALBERT J. SWEET.
